[57] **CLAIM**

The ornamental design for a watcher guard, as shown and described.

DESCRIPTION

FIG. 1 is a top plan view of a watch guard showing my new design;

FIG. 2 is a bottom plan view thereof;

FIG. 3 is a side elevational view thereof;

FIG. 4 is a left side elevational view thereof, the right side being a mirror image;

FIG. 5 is a bottom perspective view thereof in a closed position;

FIG. 6 is a bottom perspective view with a broken line showing of an environmental watch which forms no part of the claimed design; and,

FIG. 7 is a top perspective view thereof on a reduced scale, the broken lines being environmental only, and form no part of the claimed design.
